(57) **CLAIM**

I claim the ornamental design for a front bumper for an automobile, as shown and described.

DESCRIPTION

FIG. 1 is a front perspective view for a “front bumper for an automobile” showing my new design,
FIG. 2 is a rear perspective view thereof,
FIG. 3 is a front view thereof,
FIG. 4 is a rear view thereof,
FIG. 5 is a top view thereof,
FIG. 6 is a bottom view thereof,
FIG. 7 is a left-side view thereof; and,
FIG. 8 is a right-side view thereof.

1 Claim, 8 Drawing Sheets

FIG. 1

FIG. 2

FIG. 3

FIG. 4

FIG. 5

FIG. 6

FIG. 7

FIG. 8
